UNITED STATES PATENT OFFICE.

GEORGE S. HENSLEY, OF MIDDLETOWN, ASSIGNOR OF ONE-HALF TO
ZACHARIAH THOMPSON, OF CLINTON, ARKANSAS.

MECHANICAL MOVEMENT.

SPECIFICATION forming part of Letters Patent No. 298,376, dated May 13, 1884.

Application filed April 12, 1884. (No model.)

To all whom it may concern:

Be it known that I, GEORGE S. HENSLEY, a citizen of the United States, residing at Middletown settlement, in the county of Van Buren and State of Arkansas, have invented certain new and useful Improvements in Mechanical Movements, of which the following is a specification, reference being had therein to the accompanying drawings.

10 My invention has relation to mechanical movements, and more particularly to that class wherein a reciprocating is converted into an accelerated rotary motion; and the object is to so communicate the reciprocating motion 15 to a rotating crank whereby the crank will have the same or a greater throw than the stroke of the reciprocating movement, and thus a greater leverage brought to bear upon said crank; and to these ends the novelty consists in the construction, arrangement, and 20 combination of parts, as will be hereinafter more fully described, and particularly pointed out in the claim.

In the accompanying drawings the same letters of reference indicate the same parts of the 25 invention.

Figure 1 is a side elevation of an engine embodying my invention, and Fig. 2 is a plan view of the device detached.

30 A is the bed-plate or base, B the cylinder, C the piston-rod, D the fly-wheel, and E the eccentric-rod, of an ordinary horizontal engine.

F is the crank, secured to the shaft H.

35 To the outer end of the crank H is secured the usual crank-pin, G, and connected to it are two short pitmen, I I, their other ends being connected by pins i i to the levers K K, pivoted at their centers to the pin L, their inner 40 end being secured to the pitmen M M by pins or bolts n n, while the inner ends of the pitmen M M are secured to a pin, N, which is rigid with the standard O.

P is a connecting-rod, having a U-shaped

head, p p', encompassing the levers K K, so as 45 to form a bearing on either side thereof for the pin L, while the other end of the connecting-rod P is secured to the cross head R; and it will thus be seen that the reciprocating motion of the cross-head is converted into a motion of 50 the shaft H, through the medium of the connecting-rod, pitmen, levers, and crank above described.

It will further be observed by those familiar with the principle of the "lazy-tongs" herein 55 employed, that for each pair of the cross-levers K K employed the motion in inches of the cross-head will be doubled with regard to the crank, and, in the illustration shown, while the cross-head is moving one inch the crank 60 is moving two inches. If, however, a double pair of the levers K K be employed, then for every inch the cross-head travels the crank will move four inches.

In the drawings I have shown my improved 65 mechanical movement as applied to a steam-engine in place of the ordinary connecting-rod, which is dispensed with, and a much larger crank used than would be the case if the old construction were employed, whereby a greater 70 leverage is obtained upon the crank with the same pressure upon the piston.

Having thus fully described my invention, what I claim as new and useful, and desire to 75 secure by Letters Patent of the United States, is—

The combination, with the bed-plate, having standard O and shaft H, provided with crank F, of the connecting-rod P, levers K K, and pitmen I I and M M, arranged substantially 80 as shown and described.

In testimony whereof I affix my signature in presence of two witnesses.

GEORGE S. HENSLEY.

Witnesses:

J. A. HENSLEY,
JOHN GOODNIGHT.
